UNITED STATES PATENT OFFICE.

EDWARD D. ROCKWELL, OF BRISTOL, CONNECTICUT, ASSIGNOR TO THE LIBERTY BELL COMPANY, OF SAME PLACE.

DESIGN FOR A GONG FOR BELLS.

SPECIFICATION forming part of Design No. 30,990, dated June 13, 1899.

Application filed May 16, 1899. Serial No. 717,098. Term of patent 7 years.

To all whom it may concern:

Be it known that I, EDWARD D. ROCKWELL, a citizen of the United States, and a resident of Bristol, in the county of Hartford and State of Connecticut, have invented and produced a new and original Design for Gongs for Bells, of which the following is a specification, reference being had to the accompanying drawings, forming a part hereof.

- 5 **10** Figure 1 is a top or plan view of a gong for a bell, showing my new design. Fig. 2 is a view in side elevation of the gong.

The gong in which my invention is embodied is of rounded outline when seen in plan view, as shown in Fig. 1, and it is also rounded on the upper side, as shown in Fig. 2, where the gong is depicted in side view. A series of projections extend in a line around the gong, this line forming a border *a*, that 15 20 defines one side of a plain band *b*, also ex-

tending around the gong. The other side of the band *b* is defined by the edge of the gong. This line or border *a* of projections from the surface of the gong when presented in top or side view has the appearance of a row of beads. **25**

The essential feature of the design consists of a row or line of bead-like projections extending around the gong and defining one side of a plain band, also extending around the gong. **30**

Having described my invention, what I claim as new, and desire to secure by Letters Patent, is—

The design for a gong for a bell substantially as herein shown and described.

EDWARD D. ROCKWELL.
